UNITED STATES PATENT OFFICE

145,939

DESIGN FOR A PENCIL SHARPENER

Gerald D. Gulotta, Rockford, Ill., assignor to Roy W. Hays, Rockford, Ill.

Application March 13, 1946, Serial No. 127,430

Term of patent 14 years

(Cl. D74—1)

To all whom it may concern:

Be it known that I, Gerald D. Gulotta, a citizen of the United States, residing at Rockford, in the county of Winnebago and State of Illinois, have invented a new, original, and ornamental Design for a Pencil Sharpener, of which the following is a specification, reference being had to the accompanying drawing, forming part thereof.

In the drawing:

Fig. 2 is a side elevational view.

Fig. 3 is a rear elevational view looking from the left side of Fig. 2.

The essential features of my design for a pencil sharpener reside in the configuration of the housing portion.

I claim:

The ornamental design for a pencil sharpener, substantially as shown and described.

GERALD D. GULOTTA.
